(57) CLAIM

The ornamental design for a cup for drinking beverages, as shown and described.

DESCRIPTION

FIG. 1 is a perspective view of a cup for drinking beverages, showing my new design;

FIG. 2 is a front elevation view thereof; and,

FIG. 3 is a top plan view thereof.

A characteristic feature of the design resides in the position of a circle intersecting the pattern of polygons on the front of the truncated spherical cup.
